COMBINED BOTTLE AND BRUSH

Kenneth Jack Feuerbacher, 10848 Benbrook Drive,
Dallas, Tex.

Filed Sept. 4, 1962, Ser. No. 71,529

Term of patent 3½ years

(Cl. D58—9)

Fig. 1

Fig. 2

Fig. 3

Fig. 4

I claim:

The new and ornamental design for a combined bottle and brush, as shown.
